UNITED STATES PATENT OFFICE.

WILLIAM G. FLETCHER, OF BOSTON, MASSACHUSETTS.

DESIGN FOR A VASE.

Specification forming part of Design No. **7,941**, dated December 22, 1874; application filed November 20, 1874.
[Term of Patent 3½ years.]

To all whom it may concern:

Be it known that I, WILLIAM G. FLETCHER, of Boston, in the county of Suffolk and State of Massachusetts, have invented a Design for Vase, of which the following is a specification:

The nature of this design is fully represented in the accompanying photographic illustration, to which reference is made; and it relates to an ornamental form for a vase, made of porcelain, glass, or other similar ware, and mounted on any suitable base.

The design consists of a vase in the form of a coiled or twisted leaf, the stem of the leaf

constituting the bottom of the vase, and the twisted leaf the body of the vase, the whole being substantially in the form of a hollow inverted cone.

I claim—

The design for a vase, substantially as herein described, and shown in the accompanying photographic illustration.

WILLIAM G. FLETCHER.
